ATTORNEY

UNITED STATES PATENT OFFICE.

WILLIAM H. PETERSON, OF GLENDALE, WASHINGTON.

LOG-TOWING CRADLE.

Application filed April 2, 1924. Serial No. 703,694.

This invention relates to towing cradles, and more particularly to a pontoon cradle for towing logs on the seas or inland waters, and has for its principal object to provide 5 a device of that character whereby logs may be securely held together and safely and conveniently towed, which will dispense with the necessity of rafting the logs, whereby the logs may be assembled quickly and with 10 little labor and which provides for easily securing or releasing them from the cradle.

It is a fact that logs rafted in the usual manner cannot be safely towed at sea or on inland waters, except in good weather, or 15 when the logs are built into rafts that are bound together at a considerable and almost prohibitive expense. It is also a fact that with all the precautions that are taken in the transportation of logs, many rafts 20 are broken up by rough water and the logs are lost and then they become a menace to navigation. The present invention, therefore, seeks to provide a method and means for transporting logs on the water whereby 25 safety is insured and the above undesirable results are avoided.

In accomplishing these and other objects of the invention, I have provided the improved details of construction, the preferred 30 forms of which are illustrated in the accompanying drawings, wherein—

Figure 1 is a perspective view of a pontoon log towing cradle constructed in accordance with the present invention.

Figure 2 is a plan view of the same.

Figure 3 is a longitudinal sectional view taken on the line 3—3 in Figure 2, and illustrating the method of securing and of loading the logs within the cradle.

Figure 4 is a transverse sectional view taken on the line 4—4 in Figure 2, showing the gate valve in the pontoon.

Referring more in detail to the drawings—

The general plan of the present device is that of a floating dry dock and it consists of two parallel, spaced apart pontoons 1 and 2, which may be constructed of wood, metal or other suitable material and may be round or rectangular in cross-section and are made air and water tight. In a preferred form of construction, as illustrated in the present drawing, the pontoons would be made approximately two hundred feet long, ten feet deep and five feet wide, and in their parallel relation would rest upon the oppo-

site ends of and are rigidly joined by a plurality of cross beams 3, approximately fifty feet long and spaced at intervals of ten feet. These beams are held secure to the 60 pontoons by means of cables 4 that are secured about the beams and also about the ends of short beams or cleats 5 that transversely overlie the pontoons. The open space between the pontoons, in the preferred 65 construction, would be forty feet, or more, so that logs of the usual length can be floated in between them.

Secured upon the transverse beams 3 and extending parallel with the pontoons, the 70 length of the cradle, are stringers 6 upon which the logs are piled for towing.

To provide for the lowering of the cradle into the water for the purpose of loading or unloading logs therefrom, each pontoon 75 is provided with one or more gate valves, as indicated at 10, which may be moved between open and closed positions by any suitable means. In the present drawing I have shown this means to consist of vertical 80 shafts 11 that are threaded through brackets 12 on the gates and which are provided, at their upper ends, with wheels 13 whereby they may be rotated so that through the threaded connection the valves may be 85 opened or closed. When the valves are open, water will enter the pontoons and they will sink within the water according to the amount of water that is allowed to enter and will thus lower the entire device 90 so that logs may be floated onto the supporting member between the pontoons. There are also provided pipes 15 that extend into the pontoons and which connect with pumps, designated at 16, on the top of the pontoons 95 whereby the water may be discharged to cause the pontoons to rise in the water.

Assuming that the device is constructed in this manner for loading logs, water is let 100 into the pontoons by opening the gate valves until sufficient depth of water is over the stringers that logs may be floated into the space between the pontoons and cables 17 that may be resting on the bottom cross beams and between the stringers. When a sufficient number of logs to form a section 105 are in place, the free ends of the cables are brought up to the surface in the rear of the logs and are attached to a cable connection with a windlass, as designated at 18, and the 110 logs are then drawn in and around up by means of the cables and are secured tightly

in position between the pontoons as by means of the cables 19, shown in Figure 4.

When all the log sections are in place and are secure, a sufficient amount of water is pumped out of the pontoons to bring the cross beams 6 firmly against the logs, and the forward end of the cradle is then boarded across or filled by a cross section in order to maintain quiet water between the 10 pontoons while the cradle is being towed from place to place.

Upon arriving at the destination, the pontoons are towed to the desired position for unloading, the gate valves are opened so that the cradle will be lowered within the water sufficiently to permit the logs to float. They are then released by releasing the cables holding them and floated out from between the pontoons.

It is readily observed how little labor is required in loading and in releasing the logs and how securely and firmly they are held in position while being towed. Such a device is much easier handled than the ordinary log raft and insures safety, not only to the logs but to navigation.

Having thus described my invention, what I claim as new therein and desire to secure by Letters Patent, is:

1. A device of the class described com-

prising a pair of pontoons in spaced apart, parallel relation, a plurality of transverse beams secured at their opposite ends to the pontoons and joining the latter rigidly in spaced relation and stringers mounted on 35 the transverse beams, parallel with the pontoons and upon which logs may be bound for transportation, means for submerging the stringer level of said device to float logs thereabove and means for drawing in said 40 logs in cross-wise relation.

2. A log towing cradle comprising, a plurality of transverse beams in spaced relation, stringers mounted on said beams in parallel relation and extending at right 45 angles with respect to said beams, a pair of relatively long and narrow pontoons mounted upon the opposite ends of the transverse beams, means securing the beams to the pontoons, valves in the pontoons for 50 the admittance of water for submerging the stringer level of the cradle, and a cable having actuating means for drawing in logs in cross-wise relation upon said stringer and bunching them thereupon, and pumps operable to withdraw water from the pontoons.

Signed at Everett, Washington, this 18th day of January 1924.

WILLIAM H. PETERSON.
